COMBINED KNIFE HOLDER AND SHARPENER

Samuel L. McNair, Overland Park, Kans., assignor to Dazey Products Co.

Filed Jan. 22, 1973, Ser. No. 325,395

Term of patent 14 years

Int. Cl. D7—06

U.S. Cl. D7—74

Fig. 1.

Fig. 2.

Fig. 3.

Fig. 4.

Fig. 5.

FIG. 1 is a front perspective view of a combined knife holder and sharpener showing my new design;

FIG. 2 is a front elevational view of same;

FIG. 3 is a side elevational view of same; the other side being substantially identical;

FIG. 4 is a top end view of same; and

FIG. 5 is a bottom end view of same.

I claim:

The ornamental design for a combined knife holder and sharpener, as shown and described.
